UNITED STATES PATENT OFFICE.

FRANK W. MERRICK, OF BOSTON, MASSACHUSETTS.

WELT-GUIDING DEVICE FOR SEWING-MACHINES.

SPECIFICATION forming part of Letters Patent No. 550,760, dated December 3, 1895.

Application filed March 9, 1894. Serial No. 503,007. (No model.)

To all whom it may concern:

Be it known that I, FRANK W. MERRICK, a citizen of the United States, residing at Boston, in the county of Suffolk and State of Massachusetts, have invented certain new and useful Improvements in Sewing-Machines, of which the following is a specification, reference being had therein to the accompanying drawings.

10 My invention is particularly designed for use in connection with sewing-machines which are employed for sewing seams containing a welt. It is customary in making such seams to employ a welt which is prepared in the form of a continuous strip—that is to say, of some considerable length—and after two pieces of material intended to constitute parts of a boot or shoe or the like have been passed through the machine and united thereby with 15 the welt between them it is usual to successively pass through and similarly unite other pieces of material, the successive pieces being connected together by the intermediate portions of the welting-strip, which are subsequently severed. When one of the said intermediate portions of the welting-strip is presented to the stitching devices, it, being flexible and yielding, becomes forced into the 20 usual elongated hole or slot in the throat-plate by the action of the said stitching devices, and it frequently happens that the strip becomes packed and jammed into the said slot so tightly that it has to be driven out by a suitable tool.

25 My invention has for its object to remedy this disadvantage; and it consists, accordingly, in a throat-plate having the slot therein of the improved character hereinafter specified, and whereby the withdrawal of the welting-strip therefrom is facilitated and jamming is obviated.

In the drawings, Figure 1 is a view in end elevation of part of a wax-thread sewing-machine having my invention applied thereto. Fig. 2 is a view in plan of the work-rest and parts applied thereto. Fig. 3 is a view, detached, of a throat-plate embodying my invention. Fig. 4 is a view showing the usual form of throat-plate.

At 1 is the base of the machine. At 2 is 50 the post thereof. At 3 is the work-rest, consisting of a plate mounted on the upper end of the said post. At 4 is the needle-bar. At 5 is the needle. At 6 is the cast-off bar, at the upper end of which the cast-off is mounted, as 55 usual. At 7 is the awl-bar. At 8 is the awl. At 9 is the thread-carrier. At 10 is the presser-foot, and at 11 is the seam-guide, which last is held adjustably to the upper surface of the work-rest by screws 12 12, passing through 60 slots 13 13 in the shank of the same. The construction and operation of these parts are or may be as desired or usual.

At 14 is the welt-guide, it being made in one piece and being seamless, hollow, and elliptical in cross-section. It is secured to the free end of a swinging arm 15, which latter at its rear end is mounted pivotally between center screws 16 16, passing through lugs 17 17 on a supporting-plate 18, the said supporting-plate 18 being secured to the work-rest 3 by means of screws 19 19, passing through slots 20 20, formed in the supporting-plate and being capable of adjustment, so as to place the free end of the welt-guide in the desired position relatively to the line of feed.

At 21 is the throat-plate, and at 22 is the slot made through the same for the passage of the needle, &c.

Heretofore the slot 22 in the throat-plate has 80 been a simple straight slot of uniform width from end to end thereof, and when the welting-strip has become packed and jammed into the same so as to fill it the necessity has heretofore existed of arresting the machine and 85 driving out the accumulation by means of a suitable punch or tool applied from below. I form the said slot with an enlargement 221 at the outer end thereof and preferably bevel off the forward side of the enlargement, as indicated at 222 in Figs. 2 and 3. As will be obvious, when the work is drawn along in the direction of the feed such portions of the welting-strip as may become carried down into the slot 22 will be fed forward by the action of the 90 machine readily until they reach the enlargement 221, when they will at once become freed, and then will pass out without difficulty.

The beveled or inclined surface at the outer side of the enlargement facilitates the movement of the welt out of the slot as the work passes along.

5 I claim as my invention—

The combination with a welt-guide and the stitching devices of a sewing machine, of the throat-plate having the slot therein made with an enlargement at the outer end thereof

for the release and discharge of the welt-strip, 10 substantially as described.

In testimony whereof I affix my signature in presence of two witnesses.

FRANK W. MERRICK.

Witnesses:

W.M. A. MACLEOD,
CHAS. F. RANDALL.
